UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

DUMPING DOOR AND MOUNTING.

Application filed November 9, 1925. Serial No. 67,828.

My invention relates to the construction and mounting of hinged dumping doors such as are used on hopper or other species of dump cars.

5 The objects of my invention are to provide a strong and rigid door structure and to so hinge it to the car frame that the door may be applied or removed without difficulty. I also desire to provide means for adjusting the various hinge elements so that in the event that the door or the door supporting beam is not accurate, the hinges may be aligned nevertheless to permit free swinging of the door.

15 These and other detailed objects of my invention are secured by the construction illustrated in the accompanying drawings, in which—

Figure 1 is a top view of the door and 20 adjacent car structure.

Figure 2 is a side view of the door and adjacent car structure.

Figure 3 is in part a transverse section 25 through the doors and the adjacent parts of a typical hopper car upon which the doors are mounted, taken on line 3—3 of Figure 1, and in part a section through the car showing a door in end elevation.

The main face of the door consists of a 30 plate 1. The forward edge of the door is preferably formed by the top flange 2 of a one-piece casting or beam having a vertical web 3 and a lower horizontal flange 4. This beam is deepest at its ends and middle portions and decreases in depth from its middle portion outwardly, being most shallow a 35 short distance from its ends. At intervals along the beam, recesses 5 are provided to receive the ends of door stiffening members 6 which are secured to the beam through flange 2 and through suitable vertical ribs 2^a provided on the flange. Intermediate the recesses 5 reinforcing ribs 7 are provided between the face of web 3 opposite flange 4

40 and the edge of horizontal flange 2. The outer edge of flange 2 is preferably inclined downwardly to form an extended meeting surface for the corresponding edge of an adjacent door. Web 3 is inclined forwardly 45 from the middle to the ends of the door. A vertical rib 8 reinforces each end of the door and has the end stiffening channel 6^a secured thereto. Rib 8 and channel 6^a form

a door end wall below the top surface of 55 the door which serves to close the gap between the door and the car end floor.

Each stiffening member 6 and 6^a carries a hinge butt element 9, the ends of which are bifurcated to receive between them the 60 eye of an eye-bolt 10 and a removable hinge pin 11 extends horizontally through the eye of the bolt and the ears of butt 9.

In mounting the door upon the car, the eye bolt may be swung to any necessary 65 angle and extended through the supporting elements of the car frame. In the accompanying illustration in Figure 3, the supporting element of the car frame is indicated as a portion of a cast steel underframe including a main vertical flange 12, an upper horizontal flange 13, a lower horizontal flange 14, and an inner vertical flange 10. The lower surface of horizontal flange 13 is provided with bosses 17 at intervals 70 through which holes extend for the reception of eye-bolts 10. These bosses 17 are machined and each eye-bolt is provided with a shoulder 18 fitting against the machined surface of a respective boss 17. A nut 20 75 on the shank of eye-bolt 10 engages the machined upper face of a boss 23 on the underframe flange 13 and constitutes adjustable means for securing the eye-bolt in place from the upper side of the horizontal flange 13 80 of the car frame element.

This arrangement facilitates the application of the door to the frame and its removal or replacement for repairs. All of the faces of bosses 17 may be machined at one time 90 and without necessarily machining any other underframe surface. The faces of bosses 23 may be machined similarly. The hinge butt 9 extends rearwardly of the door plate 1 and is arranged so that the hinge pin 11 95 and eye-bolt 10 may be removed from the frame member and the door, and replaced independently of the other hinge elements. Furthermore, in the event of any distortion or other inaccuracies in the door parts or in the frame element 13, nuts 20 may be adjusted to secure alignment of all the hinge pins 11 throughout the length of the door. If desired, washers 19 may be inserted 100 between the shoulder 17 on the eye bolt and the boss 17 on the frame element in the event that it is necessary to drop the eye-

bolt and hinge somewhat in order to preserve the alignment referred to.

Each end of the beam located at the inner edge of the door has a projection 21 extending beyond the end of the door by which the door may be secured to the door operating mechanism (not shown) through a link 22 or other suitable connection.

Some of the elements of the car structure 10 illustrated in my present drawings are described and claimed in my copending application Serial No. 79,782, filed January 7, 1926, and I do not intend to abandon any of such elements by reason of their not being 15 claimed in the present application.

Various modifications of the details of my invention may be made without departing from the spirit of my invention, and I contemplate the exclusive use of such changes 20 as are included in the scope of my claims.

I claim:

1. In a dumping car door, a door beam having a vertical element extending along but spaced from a door edge, said element 25 being provided with openings at intervals to receive door stiffening members extending transversely of said beam.

2. In a dumping car door, a beam extending along an edge of the door and including a vertical flange substantially paralleling the door edge but spaced therefrom, there being openings in said flange at intervals along its length, and door stiffening members extending transversely of said 35 beam and through said openings.

3. In a dumping car door, a beam extending along an edge of the door and including a vertical flange substantially paralleling the door edge but spaced therefrom, 40 there being openings in said flange at intervals along its length, door stiffening members extending transversely of said beam and through said openings, and elements extending transversely of said beam and 45 bracing said edge from said flange intermediate to said stiffening members.

4. In a dumping car door, a door beam extending along but spaced from a door edge, said beam being provided with openings 50 at intervals to receive door stiffening members extending transversely of said beam, and transverse elements at intervals along said beam between said openings and bracing the adjacent door edge from said beam.

5. In a dumping car door, a door beam comprising a casting forming a door edge and adjacent door face and having a vertical reinforcing flange extending along but 60 spaced from said edge and increasing in depth intermediate its ends.

6. In a dumping car door, a door beam comprising a casting forming a door edge and adjacent door face and having a vertical reinforcing flange extending along but 65

spaced from said edge and provided with openings at intervals near the face of the door to receive door stiffening angles arranged transversely of said beam.

7. In a dumping car door, a door beam 70 comprising a casting forming a door edge and adjacent door face and having a vertical longitudinal reinforcing flange and having transverse ribs connecting said flange and face at intervals. 75

8. In a dumping car door, a door beam comprising a casting forming a door edge and adjacent door face and having a vertical longitudinal reinforcing flange and having transverse ribs connecting said flange 80 and face at intervals, said flange being provided with openings between said ribs and adjacent the door face for the reception of door stiffening members extending transversely of said beam. 85

9. In a dumping car door, a door beam forming a portion of the door face and having a downwardly extending flange along its edge inclined outwardly from a plane perpendicular to the door face so as 90 to form an extended meeting surface for the edge of an adjacent door.

10. In a dumping car door, a one piece casting comprising a portion of the door face, and a beam below the same spaced from the edge thereof, said casting including a downwardly inclined flange on the edge of the door face adapted to form an extended meeting surface for the edge of an adjacent door. 95

11. In a dumping car door, a one-piece casting extending lengthwise of the door and including a vertical beam web, a flange forming a door edge and an upper chord for the beam web, and a flange forming a lower chord for the beam web and extending inwardly of the door. 100

12. In a dumping car door, a one-piece casting extending lengthwise of the door and including a vertical beam web, a flange extending in both directions from said web and forming a door edge and an upper chord for the beam web, and a flange forming a lower chord for the beam web and extending inwardly of the door. 110

13. In a dumping car door, a one-piece casting extending lengthwise of the door and comprising a horizontal portion forming a part of the door face, a vertical web intermediate the edges of said portion, a horizontal flange on one side of the lower part of said web, and vertical transverse ribs between the opposite side of said web and said horizontal portion. 115

14. In a car, a transversely extending frame member, a dumping door with a hinged side underlying one edge of said member, a door hinge butt secured to said door side and extending therefrom, a hinge element pivoted on the end of said butt remote from said door and adapted to be moved vertically to 125 130

engage said frame member or to be disengaged therefrom independently of the other hinge members.

15. In a dumping door, a door beam comprising a casting forming a door edge and having a vertical reinforcing flange extending along but spaced from said edge, there being a horizontal rib on the lower edge of said flange extending rearwardly from the

10 door edge.

16. In a dumping car door, a one-piece casting extending lengthwise of the door and including a vertical beam web, a flange forming a door edge and an upper chord for the 15 beam web, and a flange forming a lower chord for the beam web.

17. In a dumping car door, a one-piece casting extending lengthwise of the door and including a vertical beam web, a flange forming a door edge and an upper chord for the 20 beam web, and a flange forming a lower

chord for the beam web and spaced from said upper chord.

18. In a dumping door, a door beam extending lengthwise of the door and consisting of a casting with a transverse rib at its end forming part of an end wall below the top surface of the door, a door stiffener adjacent said rib and forming an extension of said wall, said stiffener being crimped inwardly for attachment to said wall. 25

19. In a dumping car door, a door beam extending longitudinally of the door but spaced from the door edge, said beam being provided with openings at intervals to receive door stiffening members extending transversely of said beam, and vertical transverse ribs on said beam adjacent said openings for attachment of said members thereto. 35

In testimony whereof I hereunto affix my 40
signature this 26 day of October, 1925.

WILLIAM M. SHEEHAN.
